F. B. WILLIAMS

SPIDER FOR COTTON CLEANERS

Filed Aug. 23, 1922

J. M. Evans

WITNESS:

F. B. Williams
INVENTOR
BY *Victor J. Evans*

ATTORNEY

UNITED STATES PATENT OFFICE.

FRENCH B. WILLIAMS, OF LUFKIN, TEXAS.

SPIDER FOR COTTON CLEANERS.

Application filed August 23, 1922. Serial No. 583,893.

To all whom it may concern:

Be it known that I, FRENCH B. WILLIAMS, a citizen of the United States, residing at Lufkin, in the county of Angelina and State 6 of Texas, have invented new and useful Improvements in Spiders for Cotton Cleaners, of which the following is a specification.

This invention relates to cotton cleaning machines, and has particular application to 10 an attachment therefor in the nature of a spider mounted for rotation, and designed to burst the burrs and fluff the cotton, without cutting the burrs to pieces.

The nature and advantages of the invention 15 will be better understood when the following detailed description is read in connection with the accompanying drawing, the invention residing in the construction, combination, and arrangement of parts as 20 claimed.

In the drawing forming part of this application, like numerals of reference indicate similar parts in the several views, and wherein:—

25 Figure 1 is a fragmentary sectional view through the cotton cleaning machine, showing the application of the invention.

Figure 2 is a detail view of the spider.

Figure 3 is a sectional view taken on line 30 3—3 of Figure 1.

Referring to the drawing in detail, A indicates generally the spider forming the subject matter of the present invention, the spider being designed for use in conjunction 35 with a cotton cleaning machine and arranged in relation to the machine in a manner illustrated in Figure 1. The spider in-

cludes a hub 10, and a plurality of arms 11, the latter radiating from the hub and of any desired length. The spider is mounted 40 upon the shaft 12 for rotation, and each arm is rounded at its front as at 13 and based by means of a thin, tapered web 14 as illustrated. The webs terminate short of the outer ends of the arms 11, and are preferably 45 formed integral therewith. As the spider is rotated, the rounded surfaces of the arms 11 break up the bolls, and fluff the cotton without injuring the burrs. By the elimination of any sharp edges on the arms 50 of the spider, which are brought into contact with the cotton, bolls can be burst without being cut to pieces.

While it is believed that from the foregoing description, the nature and advantages of the invention will be readily apparent, I desire to have it understood that I do not limit myself to what is herein shown and described, and that such changes may be resorted to when desired as fall within 55 the scope of what is claimed.

What I claim is:—

A spider of the character described comprising a hub, webs radiating from the hub and disposed at an angle thereto, and with 60 relation to each other, an arm supported by one edge of said web, with the latter merging into the arm adjacent the outer end thereof, the corresponding inner extremities of said arms terminating in spaced relation 65 to the hub and supported at the point of juncture between the adjacent webs.

In testimony whereof I affix my signature.

FRENCH B. WILLIAMS.
